Nelson M. Howard

UNITED STATES PATENT OFFICE.

JAMES E. MCINTIRE, OF WEYMOUTH, MASSACHUSETTS, ASSIGNOR TO P. R. GLASS COMPANY, OF BOSTON, MASSACHUSETTS, A CORPORATION OF MASSACHUSETTS.

MACHINE FOR WIPE OUT BINDINGS.

1,322,591.

Specification of Letters Patent. Patented Nov. 25, 1919.

Application filed March 5, 1918. Serial No. 220,482.

To all whom it may concern:

Be it known that I, JAMES E. MCINTIRE, a citizen of the United States, residing at Weymouth, in the county of Norfolk and 5 State of Massachusetts, have invented certain Improvements in Machines for Wiping Out Bindings, of which the following description, in connection with the accompanying drawings, is a specification, like 10 reference characters on the drawings indicating like parts in the several figures.

This invention relates to machines for use in the manufacture of boots and shoes and is herein illustrated as embodied in a 15 machine for producing a so-called French edge.

It is customary in the manufacture of certain styles of boots and shoes to bind the edges of parts of the uppers with a strip 20 of fabric. To this end such a strip is stitched to the edge of the vamp, quarter or other piece of material which is to be bound, cement is applied to the strip, and then the free portion of the strip is folded 25 about the edge of the material and pressed down so that the cement will hold it firmly in place.

There are two distinct steps in the formation 30 of a French edge after the binding has been stitched to the material. First the free portion of the binding should be wiped over that portion of itself which is attached to the material until the stitches "smile", that is, until they can be plainly 35 seen; and second, the portion of the binding which then extends beyond the edge of the material should be drawn tightly about said edge and maintained taut while it is laid over on the margin of the material.

40 In my prior Patent, No. 1,278,490, granted Sept. 10, 1918, there is shown an edge-folding machine fitted for performing the second step referred to above, namely, the folding or drawing of the wiped out or 45 straightened binding over the edge of the material; and the general object of the present invention is to provide an improved machine for performing the step of wiping out or straightening the binding preparatory to the folding operation.

According to one feature of the invention, a member movable in a path approximately parallel to the plane of the work wipes the free portion of the binding over 55 that portion of itself which is attached

to the material. Conveniently the wiping member is in the form of a rotary disk having a corrugated operating face, and the work is fed to this rotary member by a co-operating feed roll and feed disk, the plane 60 of the work being approximately parallel to the plane of the disk. With this construction the free portion of the binding is turned through approximately 180° about its attached base and is pulled or wiped 65 out very effectively.

In operating upon work of this kind, it is desirable to be able to control the rate of feed. For example, when the curved 70 throat of a vamp is encountered, the rate of feed should be less. To this end, another feature of the invention comprises, in a machine of the class described, feed mechanism, a driving member, and a connection between the mechanism and member 75 such that the operator may retard the feed by pulling back on the work. Conveniently this connection comprises a friction clutch the members of which are pressed together by a spring, and means for varying 80 the tension of the spring.

These and other features of the invention, including certain details of construction and combinations of parts, will be described 85 as embodied in an illustrative machine and will be pointed out in the appended claims.

Referring now to the accompanying drawings,—

Figure 1 is a side elevation of a machine in which the present invention is embodied; 90

Fig. 2 is a perspective showing more particularly the feed mechanism and the wiper;

Fig. 3 is a perspective of a portion of the operative face of the wiper.

Fig. 4 is a perspective of the feed mechanism and wiper, showing a piece of work in process of being operated upon;

Fig. 5 is a section of a piece of work before it has been operated upon;

Fig. 6 is a section of a piece of work after 100 it has passed through the machine, and

Figs. 7, 8 and 9 are perspectives showing a modified form of wiper.

Mounted in suitable bearings in the frame 7 of the machine is a driving shaft 9 having 105 fast thereto a grooved pulley 11. This pulley has a conical clutch face formed in one side thereof to receive a correspondingly shaped clutch member on a driving pulley 13 which is loose on the shaft 9, a treadle rod 110

15 and suitable connections being provided to throw in this clutch when desired. The feed roll 17 is fast on the end of a horizontal shaft 19 having formed thereon a conical clutch member 21 which is received in a socket in a correspondingly shaped clutch member, said last-named member being integral with a grooved pulley 25 which is loose on the shaft 19. A coiled spring 27, 5 the tension of which may be varied by screwing a cap 29 to the right or left on the shaft 19, holds the members of the friction clutch in contact. The pulley 25 is driven by a belt 31 which passes around said pulley and around a small pulley 33 which is fast to a short, rotatable, horizontal shaft, not shown. Fast to this same shaft is a larger pulley 35 which is driven by means of a belt 37 from a pulley 39 on the driving shaft 9. The feed 10 disk 41, which co-operates with the cylindrical portion of the feed roll 17 is fast to a shaft 43 mounted in bearings in the frame of the machine, said shaft being provided with a collar 45 between which and the upper bearing of the shaft is located a coiled spring 47 which serves to hold the feed disk in contact with the work. The shaft 43 is splined, as indicated at 44, to the hub of a pulley 49 so that it may rise and fall in accordance 15 with the thickness of the work without disturbing the driving connection between the pulley and the shaft. A belt 53 passes around the pulley 49 and is received in the lower groove of a double grooved pulley 55 which is loose on a short upright shaft 57, 20 this pulley being driven by a belt 67 which passes over idler pulleys 69 and 71 and down around a pulley 73 fast to the shaft 19. With the construction thus far described, it will 25 be apparent that both the roll 17 and the disk 41 of the feed mechanism are driven through the friction clutch. The purpose of this construction is to permit the operator to hold back on the work at any time and 30 thus to retard the rate of feed as he may desire.

The wiper 75 is fast to a stem 77 which is 35 slideable in a sleeve 79 but is held from rotation with respect thereto by a pin 81 which passes through the stem and through diametrically opposite slots 83 formed in the sleeve 79. A coiled spring 85, located between the upper end of the stem 77 and the lower end of the screw bolt 87, serves to hold 40 the wiper 75 normally in the position shown but permits the wiper to rise to accommodate its position to the thickness of the work. The screw bolt 87 is threaded through the top of the sleeve 79 and is held in adjusted 45 position by a set nut 89. The sleeve 79 is rotatable in spaced bearings in a bracket 91, the stem 93 of which is held in adjusted angular position by means of a thumb screw 95. Fast to the sleeve is a pulley 97 and between the pulley and a hollow threaded 50

bushing 99 is a thrust ball bearing 101. The sleeve 79 is held in the position shown by means of a collar 103 which is adjustably held in place on the sleeve 79 by a set screw 105. With this construction the lower limit 70 of movement of the wiper 75 may be varied by varying the position of the collar 103 on the sleeve 79, and the angular inclination of the sleeve and consequently of the axis of rotation of the wiper may be varied by 75 loosening the thumb screw 95 and changing the angular position of the bracket 91. The pulley 97 is driven by a belt 107 which passes over two idler pulleys 109, 111 and down around the pulley 11. The idler pulleys 109, 80 111 are vertically adjustable as indicated so as to permit tightening of the belt when desired.

It will be noted that the feed disk 41 extends beneath the wiping tool 75 and that 85 when a piece of work is fed to the machine the feed disk is raised. In order to prevent it from coming into contact with the under side of the wiper 75 a slideable rod 117, the lower end of which is normally held 90 close to the upper surface of the feed disk 41 by a coiled spring 119, has an arm 121 adjustably fastened to the lower part thereof by a set screw 122, there being a yoke on the outer end of the arm which extends beneath a collar 123 formed on the stem 77 of the wiper. The rod 117 is held from angular movement in its bearings by a screw 125 which extends into a slot (not shown) in the rod and is held from downward movement 95 beyond a predetermined point by a collar 127 fast to the rod against which the lower end of the spring 119 bears. The collar 127 is adjustably held in place by a set screw and in connection with the spring 119 serves to 100 hold the rod 117 in such a position that the disk 41 may rise a predetermined amount before the wiper will be raised with it.

Fig. 5 shows the work in the condition in which it comes to the operator, said work 110 consisting of a piece of material 100, such as leather, to which a strip of binding 200 is fastened by stitches 300. Referring now to Fig. 4, the operator pulls out one end of the free portion of the binding and presents the work to the machine, as shown in said figure. The feed disk 41 and feed roll 17 carry the work forward, and the tool 75 bends the binding substantially 180° about its line of attachment and wipes it over into 115 the position shown best in Fig. 6. It will be understood that cement has been applied to the upper side of said binding as it appears in Fig. 5 and that consequently when the binding is wiped over into the position 120 shown in Fig. 6, it retains this position so that it can then be readily fed to a folding machine. In order to render the wiping member more effective its operative face may comprise a projecting annular portion 175 125 130

having formed therein corrugations or projections 177. As the wiper rotates in the direction indicated in Fig. 4 and in a path the plane of which is approximately parallel to that of the work, these projections strike a rapid succession of blows and thereby impart permanence to the bend in the binding.

In Figs. 7, 8 and 9 is shown a modified form of wiper comprising a disk 179 having radial slots 180 to receive the spring arms 181 of a spider the hub of which is adapted to be received in a circular depression in the top of the disk. When the parts are assembled, as shown in Fig. 9, a screw 183 holds the parts of the wiper together and fastens them to the lower end of the shaft 77. At this time the ends of members 185, which are carried by the spring arms 181, project beyond the lower face of the disk and serve the same purpose as the projections 177 of the disk 75, the principal difference being that the members 185 may yield individually as they pass over the work.

Although the invention has been described as embodied in a particular machine, it should be understood that the invention is not limited in the scope of its application to the particular machine which has been shown and described.

Having thus described my invention, what I claim as new and desire to secure by Letters Patent of the United States is:

1. A machine for operating upon a piece of work which consists of a piece of material to which a strip of binding is attached, having, in combination, means for supporting the work, and a member movable in a path approximately parallel to the plane of the work for wiping the free portion of the binding over that portion of itself which is attached to the material.

2. A machine for operating upon a piece of work which consists of a piece of material to which a strip of binding is attached, having, in combination, means for supporting the work, and a substantially flat-faced member for wiping the free portion of the binding over that portion of itself which is attached to the material.

3. A machine for operating upon a piece of work which consists of a piece of material to which a strip of binding is attached, having, in combination, a rotary member the operative face of which is located in a plane at right angles to its axis of rotation, and means for feeding the work to said member to cause the free portion of the binding to be wiped over that portion of itself which is attached to the material.

4. A machine for operating upon a piece of work which consists of a piece of material to which a strip of binding is attached, having, in combination, means for feeding

the work and a member rotating in a path approximately parallel to the plane of the work and operating to turn the free portion of the binding substantially 180° about its line of attachment.

70

5. A machine for operating upon a piece of work which consists of a piece of material to which a strip of binding is attached, having, in combination, means for feeding the work and a member rotating in a path approximately parallel to the plane of the work and operating to turn the free portion of the binding substantially 180° about its line of attachment, said member comprising a rigid disk.

80

6. A machine for operating upon a piece of work which consists of a piece of material to which a strip of binding is attached, having, in combination, means for feeding the work, and a member rotating in a path approximately parallel to the plane of the work and operating to turn the free portion of the binding substantially 180° about its line of attachment, said member comprising a rigid disk the operating face of which is provided with a projecting corrugated margin.

85

7. A machine for operating upon a piece of work which consists of a piece of material to which a strip of binding is attached having, in combination, a thin-edged rotary operating member, and means for feeding the work to said member in such manner that the free portion of the binding is wiped over that portion of itself which is attached to the material.

90

8. A machine for operating upon a piece of work which consists of a piece of material to which a strip of binding is attached, having, in combination, feed mechanism, mechanism for laying the free portion of the binding over that portion of itself which is attached to the material, and means for operating said feed mechanism, said means comprising a driving member, and a connection between the feed mechanism and the driving member constructed and arranged to permit the operator to retard the movement of the feed mechanism by holding back on the work.

105

9. A machine for operating upon a piece of work which consists of a piece of material to which a strip of binding is attached, having, in combination, feed mechanism, mechanism for laying the free portion of the binding over that portion of itself which is attached to the material, and means for operating said feed mechanism, said means comprising a driving member and a frictional connection between the feed mechanism and the operating means arranged to allow the movement of the feed mechanism to be retarded by resistance transmitted through the work.

110

10. A machine for operating upon a piece

120

125

- of work which consists of a piece of material to which a strip of binding is attached, having, in combination, feed mechanism, mechanism for laying the free portion of the binding over that portion of itself which is attached to the material, and means for operating said feed mechanism, said means comprising a driving member, a frictional connection between the feed mechanism and the operating means arranged to allow the movement of the feed mechanism to be retarded by resistance transmitted through the work, and means for varying the strength of the frictional connection.
11. A machine for operating upon a piece of work which consists of a piece of material to which a strip of binding is attached having, in combination, means for feeding the work, means for laying the free portion of the binding over that portion of itself which is attached to the material, and frictional means for driving the feeding means.
12. A machine of the class described, having, in combination, a feed roll, means for rotating the roll about a substantially horizontal axis, a wiping member having a corrugated working face located in proximity to the roll, and means for rotating said member about a substantially vertical axis.
13. A machine of the class described, having, in combination, a feed roll, a feed disk arranged to coöperate with the roll to feed the work, a wiper for operating progressively upon the work, and means for rotating the roll, disk and wiper.
14. A machine for operating upon a piece of work which consists of a piece of material to which a strip of binding is attached, having, in combination, means for feeding the work, a binding-engaging member having a corrugated working face, and means for causing said member to wipe the free portion of the binding over that portion of itself which is attached to the material.
15. A machine for operating upon a piece of work which consists of a piece of material to which a strip of binding is attached, having, in combination, means for feeding the work, a binding-engaging member having raised portions on its working face, and means for causing said member to wipe the free portion of the binding over that portion of itself which is attached to the material.
16. A machine of the class described, having, in combination, a wiper, means for operating the wiper, means for feeding the work to the wiper, said means including a feed member arranged to extend beneath the wiper and connections between the feed member and wiper such that raising the feed member raises the wiper.
17. A machine of the class described, having, in combination, a tool for operating upon the work, means for feeding the work to the tool, said means including a feed member arranged to extend between the tool and the work and capable of movement toward the tool, there being a free and unobstructed space between the tool and feed member, and means for preventing the feed member from contacting with the tool.
- In testimony whereof I have signed my name to this specification.

JAMES E. McINTIRE.
